UNITED STATES PATENT OFFICE.

DE WANE B. SMITH, OF DEERFIELD, NEW YORK.

DESIGN FOR A SPRAYER-BODY.

SPECIFICATION forming part of Design No. 30,293, dated February 28, 1899.

Application filed January 23, 1897. Serial No. 620,471. Term of patent 7 years.

To all whom it may concern:

Be it known that I, DE WANE B. SMITH, a citizen of the United States, residing at Deerfield, in the county of Oneida and State of New York, have invented and produced a new and original Design for an Atomizer-Body, of which the following is a specification, reference being had to the accompanying drawing, showing the same.

10 The drawing shows a perspective view of my design for an atomizer-body.

The feature of the design is the shape or configuration of the atomizer-body, as shown,

having a cylindrical portion 1, a conical portion 2, a bell-shaped portion 3, and a dependent short cylindrical portion 4.

What I claim is—

The design for an atomizer-body as herein shown and described.

In witness whereof I have hereunto set my hand, this 21st day of January, 1897, in the presence of two witnesses.

DE WANE B. SMITH.
